UNITED STATES PATENT OFFICE

2,512,415

LOOSE-LEAF BINDER

Edward F. Buenger, River Forest, and John J. Monighan, Chicago, Ill., assignors to Wilson-Jones Company, Chicago, Ill., a corporation of Massachusetts

Application May 14, 1947, Serial No. 748,076

3 Claims. (Cl. 129—24)

1

This invention relates to a loose leaf binder and particularly to a spacer adapted to simplify the assembly of the ring metal with the case.

The more expensive ring binders are provided with a spring back which firmly holds the ring plates in operative relationship during the assembly of the metal and the case of the binder. On less expensive binders, however, the spring back is omitted for economical reasons and the outer edge of the ring plates are fulcrumed in the curved edges of the cover plate. Although this structure operates satisfactorily without a spring back it has several serious disadvantages. Spacers are required between the bottom of the ring plates and the back of the binder to provide sufficient room for the toggle motion of the inside edges of the ring plates and to provide clearance between the bottom of the trigger and the binding material to keep the trigger's bottom edge from tearing the binding material.

Shouldered eyelets have been utilized as spacers, but have not been entirely satisfactory because the top of the eyelet must be spun over the cover plate to hold the spacer in proper position during the assembly of the metal with the case of the binder. This extra spinning operation adds considerably to the cost of manufacturing the binders. Another disadvantage of the eyelet is the size of the hole that must be provided in the cover plate to permit insertion of an eyelet large enough to receive the shank of a rivet that must be driven through the eyelet to secure the metal to the case of the binder. Particularly in small binders the size of the aperture is of extreme importance because the space available for such apertures is very small.

One object of our invention is to provide a strong, inexpensive spacer that may be easily positioned around a conventional rivet to furnish adequate support for the rivet and cover plate during the riveting operation. It is a further object of our invention to provide a spacer that will permit the ring plates to move between open and closed position and will also provide sufficient clearance to keep the bottom of the trigger out of contact with the binding material. Another object of our invention is to provide a spacer that does not project through the cover plate. Other objects of our invention will become apparent upon reading the following description, taken in conjunction with the accompanying drawing, constituting part of the specification, in which:

Figure 1 is a perspective view of a loose leaf binder embodying our invention;

2

Figure 2 is a cross sectional view showing the rings in closed position;

Figure 3 is a cross sectional view showing the rings in open position; and

Figure 4 is a detail perspective view of our improved spacer.

In the drawings, the reference numeral 2 indicates a case comprising a back 3 and a pair of covers 4, 5 hinged to opposite edges of the back. 10 The back 3 is apertured, as indicated at 6, in longitudinally spaced relationship to receive a plurality of conventional rivets or eyelets 7 by means of which a ring metal 8 is secured to the back of the case. The back may be chipboard in the most inexpensive binders, or the binder may be provided with a fiber or steel binding back. In either case the binding back is bound into the case and forms part of the back of the binder.

The ring metal includes a pair of ring plates 9 to each of which a plurality of mating ring sections 10 is swaged. The ring plates 9 are arranged in edge to edge relationship with their outer edges fulcrumed inside the longitudinal edges of a cover plate 11. The edges of the cover plate 11 are turned inwardly, as indicated at 12, to prevent accidental displacement of the ring plates 9. The cover plate is apertured, as indicated at 13, to fit over the rivets 7. The cover plate 11 is also notched at its outer edge adjacent 25 each ring section 10, as indicated at 14, Figure 1, to provide room for the ring sections to open and close. Conventional triggers 15 and 16 may be secured to opposite ends of the ring plates to facilitate opening and closing of the ring sections.

35 A spacer 17, having an aperture 18 with an inside diameter slightly larger than the outside diameter of the rivet 7 is positioned over each rivet after it has been inserted through the aperture 6 and before the ring plates 9 and cover plate 11 are positioned. The preformed head 19 of the rivet or eyelet is positioned outside the back 3. The spacer includes circumferential ribs 20 and 21 with a neck 22 of reduced circumference spaced therebetween. The spacer 17 is so dimensioned 40 that its rib 20 is positioned in engagement with the underside of cover plate 11 when the ring binder is completely assembled. The ring plates 9 have semi-circular notches 23 cut out from their inner edges in mating relationship to provide clearance for the spacer. The notches 23 fit around the neck 22 with sufficient clearance to permit the inner edges of the ring plates to move vertically relative to the spacer when the ring sections are moved between open and closed position. The inner edges of the notches 23 engage

the underside of the rib 20 when the ring sections are moved to open position and the top surface of rib 21 when the ring sections are moved to closed position. The top 24 of the rivet or eyelet 7 is peened over the cover plate 11 adjacent aperture 13 to anchor the ring metal solidly to the back 3. The spacer 17 furnishes support to prevent the collapse of either the rivet or the cover plate during the riveting operation.

Although we have described a preferred embodiment of our invention in considerable detail, it will be understood that the description is intended to be illustrative, rather than restrictive, as many details may be modified or changed without departing from the spirit or scope of the invention. Accordingly, we do not desire to be restricted to the exact construction described, except as limited by the appended claims.

We claim:

1. In a loose leaf binder, a back member, a cover plate, a plurality of rivets securing said cover plate to said back member, a pair of ring plates fulcrumed in said cover plate, and a spacer positioned on each of said rivets and fixed relative to said back member and said cover plate, said spacers having circumferential ribs engaging said ring plates to limit their vertical movement.

2. In a loose leaf binder, a back member, a cover plate positioned above said back member, said cover plate having downturned longitudinal edges, a pair of ring plates having their inner edges arranged in side by side relationship and their outer edges fulcrumed in the downturned longitudinal edges of said cover plate, the inner edges of said ring plates having registering

35

notches co-operating to form an aperture, a spacer positioned on said back member and having a reduced neck passing through said aperture, and a rivet passing through said back member, spacer and cover plate, the upper end of said spacer being positioned below said cover plate and engaging its undersurface to support it during the riveting operation.

3. In a loose leaf binder, a back member, a cover plate positioned above said back member, said cover plate having downturned longitudinal edges, a pair of ring plates having their inner edges arranged in side by side relationship and their outer edges fulcrumed in the downturned longitudinal edges of said cover plate, the inner edges of said ring plates having registering notches co-operating to form an aperture, a spacer positioned on said back member and passing through said aperture, and a pair of circumferential ribs on said spacer, said ribs engaging the inner edges of said ring plates to limit their vertical movement in either direction.

EDWARD F. BUENGER.
